UNITED STATES PATENT OFFICE.

ISAIAH S. MARSHALL, OF DES MOINES, IOWA.

MINE DRILLING MACHINE.

Application filed January 21, 1925. Serial No. 3,774.

To all whom it may concern:

Be it known that I, ISAIAH S. MARSHALL, a citizen of the United States, and a resident of Des Moines, in the county of Polk and State of Iowa, have invented a certain new and useful Mine Drilling Machine, of which the following is a specification.

The purpose of my invention is to provide a mine drilling machine of simple construction, having certain advantages over the machines now in use.

More particularly, it is my object to provide a machine having the parts so constructed and arranged that a horizontal hole can be drilled close to the top of the entry room, the operating crank handle or other operating portion of the machine being arranged below the drill.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 shows a side elevation of a mine drilling machine embodying my invention.

Figure 2 shows a rear elevation of the same.

Figure 3 is a detailed, plan view of part of the mechanism, parts being shown in section, taken on the line 3—3 of Figure 1.

Figure 4 is a detailed, sectional view taken on the line 4—4 of Figure 1; and

Figure 5 is an elevation, partly in section, taken on the line 5—5 of Figure 1.

Miners use a hand drill for drilling the holes for the explosive. This drill includes an upright frame, comprising two spaced side members indicated in the accompanying drawings by the reference numeral 10 connected at their upper and lower ends by caps 11 and 12.

The caps are provided with vertical journals 13 and 14. In the journal 14 of the lower cap 12 is slidably received a rod 15 designed to rest on the floor and be vertically adjustable in the journal. A set screw 16 is used for locking the rod 15 in the cap 12.

A rod 17 is screw-threaded and has a screw-threaded connection with the journal 13 and projects upwardly thereof. In the rod 17 is a handle 18 for rotating it.

It will be seen that the parts are adjusted approximately to correct position. Then the

frame is set up, as shown in Figure 1, with the rod 15 resting on the floor 19 and with the rod 17 adjacent to the roof 20.

The handle 18 is then manipulated for screwing the rod 17 out of the cap 11 until the rods 15 and 17 tightly engage the floor 19 and the roof 20.

Mounted between the sides 10 of the frame is a two-part bearing, indicated generally at A, comprising the lower member 21 and the upper member 22.

The lower member 21 has laterally projecting ears 23 received between pairs of laterally projecting ears 24 on the upper bearing member 22.

Projecting laterally from the ears 23 are spindles 25 preferably provided with heads 26. In the forward edges of the frame members 10 are vertically spaced notches 27.

It will be understood that the notches 27 of the respective side members 10 are arranged in opposite horizontally aligned pairs.

The spindles 25 are selectively inserted in any opposite pair of notches 27. This permits the adjustment of the bearing A to different heights with relation to the frame.

The bearing A is screw-threaded to receive a screw-threaded rod 28, which has opposite longitudinal grooves 29.

The drill bit 30 is fastened as at 31 to the forward end of the threaded rod 28. On the rod 28 adjacent to the rear side of the frame is a sprocket 32, having the hub 33, which is screw-threaded to coact with the rod 28 and which is provided with feathers or the like 34, as shown in Figure 2, projecting into the grooves 29, so that when the sprocket 32 is rotated, its screw-threaded connection with the rod 28 will force the rod 28 forwardly toward the face 35, for the reason that the feathers cause the rod 28 to rotate when the sprocket is rotated.

The hub 33 abuts against the bearing A. The parts just described do not in themselves alone form my present invention, since with the exception of the sprocket 32 they are old in this kind of a machine.

In the ordinary machine, a beveled gear is mounted on the rod 28 and is arranged to cooperate with another suitably mounted beveled gear operated by a crank handle and arranged in mesh with the first beveled gear.

The crank handle is so connected with the bearing A in the ordinary machine that when the bearing A is near the top of the

frame 10, the crank handle is near the top of the frame 10.

In order to drill a hole near the top of the entry room with the ordinary machine, a 5 hole must be made inclined so as to let the crank handle operate without striking the roof.

It is my purpose to locate the operating handle substantially below the bearing A, 10 so that the drill may enter the face 35 for making a horizontal hole 40.

In order to accomplish this purpose, I provide a shaft 41 having the reduced end portion 42.

15 On the reduced end portion is a plate 43 (see Figure 4) adjacent to the shoulder 44 of the shaft 41.

On the shaft 41 adjacent to the plate 43 is a sprocket 45 having preferably a squared 20 projecting hub 46 on which the crank 47 may be placed. The crank 47 has a spaced series of squared holes 48 to receive the hub portion 46.

The reduced portion 42 of the shaft 41 is 25 extended between the frame members 10 with the plate 43 resting against the rear edges of the frame members 10. A second plate 49 is then placed on the reduced shaft portion 42 adjacent to the front edges of the 30 frame members 10 and a suitable wing nut or the like 50 is screwed onto the forward screw-threaded end 51 of the reduced shaft portion 42 for locking the plates 43 and 49 to the frame members 10.

35 On the sprockets 32 and 45 is a sprocket chain 52.

It will be seen that the sprocket 45 may 40 thus be adjusted vertically on the frame to correspond with the vertical adjustment of the bearing A.

The operating handle is thus located substantially below the bearing A. This permits the drill to be placed in horizontal position close to the roof and permits the 45 drilling of a horizontal hole 40.

There is thus secured a very important advantage over what can be done with a drill which must be arranged to cut inclined holes in order to permit operation of the crank handle.

50 In the coal, there are sulphur spots. These are usually substantially horizontal.

If the drill is arranged horizontally, the hole can be drilled in such a way as to miss the sulphur spots. The sulphur spots are very 55 hard and difficult to drill through, and so by the use of my device, the hard drilling through the sulphur spots can be avoided.

Furthermore, it is very difficult to drill 60 through the sulphur spots at an angle, and this difficulty I avoid with my device.

It is very frequently the case that the coal near the roof is quite soft, whereas it becomes harder farther down from the roof. Thus it follows that by being able to drill 65 a horizontal hole near the roof, the drilling operation is much easier than is the case where a slanting hole must be drilled partially through the harder coal, or where, if a horizontal hole is drilled, it must be located farther down from the roof.

My device therefore reduces the labor of drilling the upper holes.

Changes may be made in the details of the construction of my device without departing 75 from the real spirit and purpose of my invention, and it is my intention to cover by my claim, any modified forms of structure or use of mechanical equivalents which may be reasonably included within its scope. 80

I claim as my invention:

In a drill of the kind described, an upright frame, means for securing the frame between a floor and a roof, a bearing structure mounted on the frame for vertical adjustment thereon, a threaded rod mounted in said bearing in screw-threaded cooperation therewith, a drill secured to said rod, a screw-threaded sprocket mounted on said rod, said sprocket and rod having a non-rotatable sliding connection as well as the screw-threaded connection, a second sprocket 90 below the first sprocket in alignment therewith, a chain and sprocket means for operating said second sprocket, and means for 95 adjustably mounting the second sprocket on the frame, said means comprising a shaft on which the second sprocket is mounted having a reduced end, plates on said reduced end spaced from each other for receiving the 100 frame between them, and means for locking said plates on said frame.

Des Moines, Iowa, November 6, 1924.
ISAIAH S. MARSHALL.
